UNITED STATES PATENT OFFICE.

WILLIAM B. FENN, OF COLUMBUS, OHIO, ASSIGNOR TO THE WEDDIT COMPANY, OF COLUMBUS, OHIO, A CORPORATION OF OHIO.

COOKING OR STERILIZING MACHINE.

1,377,245.

Specification of Letters Patent. Patented May 10, 1921.

Application filed April 21, 1913. Serial No. 762,555.

To all whom it may concern:

Be it known that I, WILLIAM B. FENN, a citizen of the United States, residing at Columbus, in the county of Franklin and State 5 of Ohio, have invented a certain new and useful Improvement in Cooking or Sterilizing Machines, of which the following is a specification.

The object of this invention is to provide 10 an improved machine for sterilizing or cooking perishable materials and especially foods, as for example, corn cut from the cob, tomatoes, peas, etc. My object more particularly is to provide a construction in which 15 the cooking or sterilizing is effected thoroughly and more quickly and to this end I provide, as herein shown, instrumentalities whereby the cooking or sterilizing agent is delivered from a device having motion and 20 whereby more room is provided for the expansion and agitation of the materials than is provided by the container in which they are placed in the machine for treatment.

The invention is embodied in the example 25 herein shown and described, the features of novelty being pointed out in the claims appended to the description.

In the accompanying drawings—

Figure 1 is a central vertical section of the 30 machine.

Fig. 2 is a horizontal section on the line $\alpha-\alpha$ Fig. 1.

Fig. 3 is a vertical section through one of the scrapers.

Fig. 4 is a plan view of a fraction of a 35 sterilizing machine illustrating means for causing the rotation of the shafts and the members they carry used in the treating chamber.

In the views 10 designates a cylindrical receiver having a hollow head 11 secured thereto by bolts like that at 12 and forming a steam induction chamber 11^a. Secured to the lower side of the head 11 within the receiver is a wall 13 having a downwardly projecting perforated rim or wall 13^a and within and parallel to said rim or wall an imperforate wall or rim 13^b. Threaded onto the lower edge of the rim 13^a is a horizontal 45 wall 15 that, around its center, is provided with numerous perforations 15^a forming a screen. The space between the walls 13 and

15 may be said to be a steam eduction chamber. The upper side of the wall 15 is tapered toward its center. The lower side of 55 the wall 15 is provided with a downwardly extending cylindrical wall 16 of somewhat smaller diameter than that of the wall 15 so as to provide a space around it. Threaded into the rim of the wall 15 is a thin wall or 60 cylinder 17 fitting within the cylindrical receiver 10, said cylinder 17 having an inwardly projecting flange 17^a forming a stop. There is thus provided between the walls 16 and 17 an annular chamber in which fits a 65 cylindrical body 18 having at its upper end an outwardly projecting flange 18^a capable of abutting against and being stopped by the flange 17^a when said body 18 is caused or permitted to descend. The upper end of the 70 cylinder 17 is perforated at 17^b to admit pressure to operate on the body 18 as hereinafter described. The lower end of said body 18 has an annular seat 18^b and a flared portion 18^c leading to said seat to properly 75 direct or adjust the can so that the annular seat 18^b shall fit closely thereon when the parts are in position for the cooking or sterilizing operation. 19 designates a can or receptacle which is shown in the described 80 position. The can or receptacle is shown as supported upon a holder 20 adapted to close the lower end of the receiver, a packing ring being shown at 21 to make the closure tight.

Supported between suitable collars in a suitable bearing at 22 is a shaft 23 that extends axially of the receiver, through a suitable stuffing box on the head 11 into the steam induction chamber 11^a. Threaded onto the lower end of the shaft 23 in the induction 90 chamber is a vertical tube 24 that extends through the wall 13 into the aforesaid eduction chamber. Said tube 24 is perforated in that portion standing in the induction chamber to admit steam to it, and in that portion standing in the eduction chamber said tube is provided with a downwardly flared petticoat screen or baffle 25. The lower margin of the petticoat lies rather close to the upper side of the wall 15. 95

Threaded into the lower end of the tube 24 is a long vertical nozzle 26 perforated at numerous points and provided with several lateral horizontal tubular branches 27 also per-

forated so that steam under pressure admitted to the nozzle 26 is also admitted to the lateral branches 27 and jets from both. The upper portion of the nozzle 26 just 5 below the horizontal perforated wall 15 is provided with two horizontally extending tubular branches 28 each of which has a scraping edge or blade 28^a (see Fig. 3) that lies close to the lower side of the wall 15. 10 As will be explained later herein the branches 28 are swung around and below the lower side of the wall for the purpose of keeping that wall clear of matters adapted to clog the holes therein. This result is also 15 aided by the upwardly inclined perforations 28^b through which steam is ejected against the lower side of the wall. Secured to each of the extremities of the tubular branches 28 is a vertically arranged knife or scraper 29. 20 working on the inner side of the cylindrical wall 16, for the purpose of keeping it clean, said knives or scrapers being inclined toward said wall with their forward edges nearer the wall so as to increase their effectiveness for this purpose. The shaft 23 above the stuffing box on the head 11 is provided with a sprocket wheel 30 to engage a sprocket chain 31 by which the said shaft and the members carried by it are rotated. 25 It is my present purpose to employ several of these cooking or sterilizing chambers arranged in a circular series to be carried around a central valve through which a supply of steam or other sterilizing agent can 30 be passed or controlled to each of the chambers. I have described and shown such a machine in an application for patent of the United States, filed May 2, 1912, S. No. 694,716. Because the chambers are moved 35 40 the chain may be held stationary and the motion imparted to the shaft 23 may be sufficient, depending on the motion of the series of chambers, but the motion of the shaft can be increased as desired by driving the chain at the necessary speed in a direction contrary to that of the series of chambers, and conversely if the speed of the series of chambers be so great as to impart too 45 much speed to the shafts 23 the speed can 50 be diminished by driving the chain in a direction coinciding with that of the chambers to secure the desired speed of the shafts 23. In Fig. 4 is illustrated an arrangement 55 of the chain to drive fewer than the whole number of the shafts 23. This arrangement is desirable because it is unnecessary and perhaps inconvenient that the shafts 23 be operated while a chamber is being supplied with a can of material to be treated or while 60 a can that has been treated is being removed.

32 designates a threaded hole for connecting the steam supply pipe to the induction chamber. 33 is a similar hole for connecting an exhaust pipe, which pipe, as in the 65 construction described in my aforesaid

former application for patent can lead to the induction chamber of an adjoining receiver. 34 designates a similar hole for admitting steam pressure to cause the member 18 to follow the can down and permit the 70 settling of the material treated in the can. 35 designates a similar hole for the admission of pressure about the exterior of the can to offset that in the interior of the can and prevent possible rupture thereof by the 75 interior pressure of the treating agent.

In practice my present purpose is to use steam as the cooking or sterilizing agent but any other suitable gaseous sterilizing agent can be used. The can containing the material to be treated is placed on the support 20 and that member raised to close the receiver. This operation raises the member 18 which normally is down by gravity. Steam is then admitted at 32 and discharges 80 through perforations in the nozzle 26 and its branches 27 and 28. The pressure of the steam if sufficient causes the material (corn cut from the cob for example) to boil up into the cavity of the cylinder 16 and the 85 rotation of the nozzle and its branches insures the thorough penetration of all parts of the material by the steam. The vertical knives tend to keep the walls of the cylinder 16 clear of the material and the horizontal 90 scrapers 28^a and steam from branches 28 tend to keep the perforations 15^a clear of material so that steam can issue to the education chamber. The petticoat screen 25 tends 95 to clarify the steam passing into the education chamber, the fluids returning through perforations 15^a to the can. The baffle wall 13^b and the perforated wall 13^a supplement the petticoat baffle in clarifying the exhaust. 100

What I claim is:—

1. In sterilizing means, the combination with a receptacle for the material to be sterilized, of a perforated nozzle through which the sterilizing agent is applied to the material in the receptacle, said nozzle and receptacle being adapted to have relative vertical movement to bring the nozzle into or out of the receptacle, and means for rotating the nozzle during the sterilizing operation. 105

2. In sterilizing means, the combination with a receptacle for the material to be sterilized, of a nozzle having a laterally extending perforated branch through which the sterilizing agent is applied to the material 110 in the receptacle, said nozzle and receptacle being adapted to have relative vertical movement to bring the nozzle into or out of the receptacle, and means for rotating the nozzle. 115

3. In sterilizing means, the combination with a receptacle for the material to be sterilized, of a nozzle having a plurality of laterally extending perforated branches through which the sterilizing agent is ap- 120

plied to the material in the receptacle, said nozzle and receptacle being adapted to have relative vertical movement to bring the nozzle into or out of the receptacle, and means 5 for rotating the nozzle.

4. In sterilizing means, the combination with a receiver, of means in the receiver for holding a vessel containing the material to be sterilized and walls forming a chamber in the receiver above the vessel into which the material in the vessel can rise.

5. In sterilizing means, the combination with a receiver, of means in the receiver for holding a vessel containing the material to be sterilized, walls forming a chamber in the receiver above the vessel into which the material in the vessel can rise, and a perforated nozzle for applying the sterilizing agent mounted to turn in said chamber.

20 6. In sterilizing means, the combination with a receiver, of means in the receiver for holding a vessel containing the material to be sterilized, walls forming a chamber in the receiver above the vessel into which the material in the vessel can rise, and a nozzle having a perforated lateral branch for applying the sterilizing agent mounted to turn in said chamber.

30 7. In sterilizing means, the combination with a receiver, of means in the receiver for holding a vessel containing the material to be sterilized, walls forming a chamber in the receiver above the vessel into which the material in the vessel can rise, a rotary perforated nozzle for applying the sterilizing agent to the material and means for removing accumulating material from the wall of said chamber.

40 8. In sterilizing means, the combination with a receiver, of means in the receiver for holding a vessel containing the material to be sterilized, walls forming a chamber in the receiver above the vessel into which the material in the vessel can rise, the upper of said walls being perforated, a nozzle for applying the sterilizing agent to the material, and means for removing material accumulating on said upper wall.

50 9. In sterilizing means, the combination with a receiver, of means in the receiver for holding a vessel containing the material to be sterilized, walls forming a chamber in the receiver above the vessel into which the material in the vessel can rise, the upper of said walls being perforated, a nozzle for applying the sterilizing agent to the material, and means for removing material accumulating on said wall consisting of a rotated laterally extending tube having a jetting perforation inclined toward said wall and a scraping device to coöperate therewith.

60 10. In sterilizing means, the combination with a receiver, of means in the receiver for holding a vessel containing the material to be sterilized, walls forming a chamber in

the receiver above the vessel into which the material in the vessel can rise, the upper of said walls being perforated, means in said chamber for applying the sterilizing agent to the material, an eduction chamber in the 70 receiver above said upper perforated wall, and a perforated baffle in said eduction chamber above said perforated wall.

11. In sterilizing means of the kind described, a receiver for the material to be 75 sterilized having a treating chamber and means therein for applying the sterilizing agent, said receiver formed with an eduction chamber for conducting away the sterilizing agent, said eduction chamber containing two annular perforated baffles intercepting the discharge from the treating chamber and an imperforate annular wall separating said perforated baffles.

12. In sterilizing means, the combination with a plurality of receivers for the material to be sterilized, of rotary devices in the receivers for applying the sterilizing agent to said material, means for rotating all of said rotary devices but fewer than the whole 90 number simultaneously.

13. Apparatus for sterilizing material comprising a means for supplying a sterilizing agent to the material in the vessel and providing a chamber in which the material may expand, said chamber having an 95 opening approximately equal to the cross-section of the vessel.

14. Sterilizing apparatus comprising means for directly introducing steam to the 100 product, a chamber into which the product may rise, a normally open outlet for the steam, and a separator to remove moisture from the steam flowing from said chamber.

15. Apparatus for sterilizing material, 105 comprising a means for supplying a sterilizing agent under pressure and adapted to agitate the material, and automatic means for introducing said means into the material.

16. Apparatus for sterilizing material, comprising a receptacle for the material, a chamber, and automatic means for presenting said chamber to said receptacle to permit the material to expand therein.

17. Apparatus for sterilizing material in a vessel, comprising means for engaging the open end of the vessel, said means being chambered to permit the material to rise therein, means for supplying a sterilizing agent in such a manner as to cause such material to rise, and means for freeing the chamber of such material after it has risen.

18. Apparatus for sterilizing material in a vessel, comprising means for engaging the open end of the vessel, said means being chambered to permit the material to rise therein and the wall of said chamber being perforated, means for supplying a treating fluid under pressure, means for releasing 130

such pressure agent after treatment through the aforesaid perforations.

19. Apparatus for sterilizing material in a vessel, comprising means for engaging the open end of the vessel, said means being chambered to permit the material to rise therein, means for supplying a fluid treat-

ing agent, and means for baffling the liquid from the fluid treating agent when the latter agent is released.
